UNITED STATES PATENT OFFICE.

WILLIAM ROBERT McCUALEY, OF LURGAN, IRELAND, ASSIGNOR TO HENRY MATIER & COMPANY LIMITED, OF BELFAST, IRELAND.

PUNCH ATTACHMENT FOR HEMSTITCH-MACHINES.

1,109,857.

Specification of Letters Patent.

Patented Sept. 8, 1914.

Application filed November 26, 1913. Serial No. 893,106.

To all whom it may concern:

Be it known that I, WILLIAM ROBERT McCUALEY, a subject of the King of Great Britain, residing at Lurgan, county Armagh, Ireland, have invented a certain new and useful Punch Attachment for Hemstitch-Machines, of which the following is a specification.

This invention relates to hemstitch sewing machines.

Under my invention I provide an automatic intermittent punch attachment for hemstitch sewing machines which is operable with and adapted to be adjustably carried by the needle bar and held out of and brought into action at the required times by cam or equivalent mechanism actuated by or from any suitable moving part of the machine and as the punch is carried by the needle bar any adjustment of the latter automatically and correspondingly adjusts the punch attachment which also can be used for punch or "shire" work without changing.

In the accompanying drawings:—Figure 1 is a side view of the machine showing the needle vibrating mechanism and the mechanism for controlling the operation of the punch in accordance with my invention. Fig. 2 is a front elevation of the needle bar of the machine to show the method of connecting and operating the punch with the needle bar. Fig. 3 is a plan view of the punch operating or controlling mechanism.

In carrying out my invention as shown in the drawings I provide a punch holder and slide a^1 and slidably support same on the needle bar b of the sewing machine the punch holder a^1 being adapted to adjustably and removably support a punch a of any desired size and shape. The punch holder a^1 is adapted to slide on the needle bar b and a spring or equivalent c is provided in or in connection with the needle bar (in the example shown it is inside the needle bar) and at its lower end it is in contact with the punch holder a^1 at a^3 and causes same to move with the needle bar, the holder a^1 being provided with a projection a^2 whereby when required it can be prevented from moving down along with the needle bar under the action of this spring c in order to keep the punch a , during certain parts of the sewing operation, out of action. This holding up of the punch holder a^1 is in the example

shown in the drawings intermittently and automatically effected at the required times by providing a projecting portion d^1 on the periphery of the usual vibrating cam d , one end f^1 of the lever f being adapted to bear on the periphery of the cam d so that it is operated or moved by the projection d^1 and gives a corresponding movement to a link or rod g pivoted thereto at one end g^1 , the other end g^2 of the link g being slidably supported in a slot in the machine head and near this end g^2 a trip g^3 is adjustably secured to the link g , the arrangement being such that when the end f^1 of the lever f is off the projecting portion d^1 of the cam d the trip g^3 is moved under the projection a^2 on the punch holder and the punch a is at such times held up against the action of the spring and out of action during the required period and preventing the punch moving with the needle bar b and needle as the latter moves down through the cloth and when the end f^1 of the lever f is on the projection d^1 of the cam d the trip g^3 is moved clear of the projection a^2 of the punch holder a^1 and so allowing the latter and the punch a to be forced down by the spring c and thereby causing the punch a to pierce an opening or hole of the required size and shape in the material being sewn. The point at which the trip g^3 comes into or goes out of action can be controlled by adjusting the trip g^3 at the end g^2 of the link or rod g .

By means of my invention as above described "punch" or "shire" stitching can be done on the same machine and the necessity for separate machines or separately operated punch mechanism is thereby obviated and the punch can be timed to come into action as required, usually at every third downward movement of the needle in hem or shire stitching, while at the same time any adjustment of the timing or movements of the needle bar automatically adjusts the punch owing to the fact that the latter is carried by the needle bar and therefore moves therewith although being free to move or be moved relatively thereto as required.

Having thus fully described my invention, what I claim as new and desire to secure by Letters Patent is:

1. The combination with a hemstitch sewing machine of a needle bar, a punch, a punch holder slidably supported on the needle bar of the machine, spring means in con-

nection with the needle bar of the machine and with the slidable punch holder whereby the latter is normally pressed downward and caused to move with the needle bar as the latter is reciprocated, a projecting part on the punch holder, a cam lever and link mechanism operated thereby and a trip operated by the lever and link mechanism and adapted when put into action thereby to intercept the descent of the punch holder at the required times and to hold the punch out of action.

2. The combination with a hemstitch sewing machine of a punch, a punch holder slidably supported on the needle bar of the machine, spring means in connection with the needle bar of the machine and with the slidable punch holder whereby the latter is normally pressed downward and caused to move with the needle bar as the latter is reciprocated, a projecting part on the punch holder, a link slidably supported in the machine head, a trip adjustably supported on the link, a lever pivotally connected at one end to the other end of the link and itself pivotally supported on the machine framing, a needle bar vibrating cam on which the other end of the lever rests and which is provided with a projecting portion adapted when the lever end engages it to move the lever and link and the trip connected therewith so

that the latter is moved out of the way of the projecting part of the punch holder, thereby allowing the descent of the punch holder during such times as the lever end is in contact with the projecting portion of the periphery of the cam, and spring means for maintaining the lever end in contact with the periphery of the cam.

3. The combination with a hemstitch sewing machine of a hollow needle bar, a punch, a punch holder slidably supported on the needle bar of the machine, a spring accommodated in the interior of the needle bar and bearing at its lower end on the ~~slidable~~ punch holder whereby the latter is normally pressed downward and caused to move with the needle bar as the latter is reciprocated, a projecting part on the punch holder, a cam lever and link mechanism operated thereby and a trip operated by the lever and link mechanism and adapted when put into action thereby to intercept the descent of the punch holder at the required times and to hold the punch out of action.

In testimony whereof I affix my signature in presence of two witnesses.

WILLIAM ROBERT McC AULEY.
